JOHN W. BROWN, OF LAKWOOD, OHIO, ASSIGNOR TO NATIONAL CARBON COMPANY,
OF CLEVELAND, OHIO, A CORPORATION OF NEW JERSEY.

METHOD OF SOFTENING THE ENDS OF ELECTRODES AND OTHER CARBON ARTICLES.

1,084,129.

Specification of Letters Patent. Patented Jan. 13, 1914.

Application filed June 10, 1912. Serial No. 702,698.

To all whom it may concern:

Be it known that I, JOHN W. BROWN, a resident of Lakewood, in the county of Cuyahoga, in the State of Ohio, have invented new and useful Improvements in the Method of Softening the Ends of Electrodes and other Carbon Articles, of which the following is a clear and exact description.

This invention relates to a method of softening the ends of furnace electrodes so that a threaded connection can be made. The method is not, however, limited to this particular application as it can be used to locally soften any carbon article for any purpose.

It is frequently necessary to join carbon articles together in such a way that good electrical contact is made. An instance of this is in furnace electrodes. When a furnace electrode had been consumed to such an extent that it no longer projected sufficiently into the furnace, it was formerly the practice to throw away the stub end. This stub extended through the thick furnace wall sufficiently to enable a proper contact to be made with the bus bars, and hence it was of sufficient length to entail considerable loss when it was thrown on the scrap heap. The practice at the present time is to make large furnace electrodes in sections with male and female screws on the ends so that when a furnace electrode is partially consumed a section can be screwed onto the end projecting from the furnace wall. The connections are then transferred to the extreme of the newly placed section and the electrode is pushed farther into the furnace. In this way it is possible to use up the entire electrode, avoiding the loss that formerly resulted from throwing away the stub ends.

Furnace electrodes are baked very hard, so that practically the only way that threads can be cut on the ends is by means of small emery wheels. Before the threads can be cut in this way, however, it is necessary to chip away the outside portions to form a socket in one end and a tenon or dowel on the other end. That method of forming the screw connections is slow and expensive.

It is well known that graphite electrodes

are soft and easily worked, and when furnace electrodes are made of graphite there is very little trouble in machining the ends of the sections. However, it is a waste of energy to entirely graphitize large electrodes merely for the purpose of machining the ends. By old processes of graphitization, it is not possible to graphitize only a part of a carbon article as the whole article was submitted to a slow heat which finally graphitized it through all its parts. I have found that by using a heavy current that carbon can be converted into graphite in a very short time. By using current densities of approximately 5000 amperes per square inch I have been able to graphitize carbon in 20 seconds. This quick graphitization of carbon enables me to carry out my method of softening certain parts of furnace electrodes in a very short time, while the remaining parts are substantially unchanged.

Referring to the drawings: Figure 1 represents more or less diagrammatically an arrangement for softening a core in the end of a furnace electrode. Fig. 2 is a cross section on the line A—A of Fig. 1. Fig. 3 is a sectional view of an arrangement for softening the outer shell of the end of the electrode. Fig. 4 is a section taken on the line B—B of Fig. 3. Fig. 5 is an arrangement for softening the core in one end of the electrode at the same time that the outer shell of the other end of the electrode is being softened. Fig. 6 is a sectional elevation of an arrangement for treating a number of electrodes at the same time. Fig. 7 is a view of the box shown in Fig. 6. Fig. 8 is a longitudinal section of a furnace electrode showing a threaded socket on one and a threaded tenon on the other. Fig. 9 is a view of the resistor to be used with rectangular electrodes. Fig. 10 is a cross section of another modification of a terminal electrode to be used in the process. Fig. 11 is a cross section of another modification of a terminal electrode. Fig. 12 is a sectional view of a modified form of terminal electrode. Fig. 13 is a sectional view of a somewhat similar modification to that shown in Fig. 12. Fig. 14 shows a modified form of resistor adapted to slip over the end of the

electrodes. Fig. 15 is a sectional view taken on the line B—B of Fig. 14. Fig. 16 is a modification somewhat similar to that shown in Fig. 14. Fig. 17 is an end view of the 5 resistor 21 shown in Fig. 16. Fig. 18 is a sectional view of a modification of Fig. 16. Fig. 19 is also a modification of Fig. 16. Fig. 20 is a further modification of the resistor shown in Fig. 16.

- 10 Referring to Fig. 1, 1 represents a furnace electrode, one end of which is to be softened. The resistor 2, approximately the size and shape in cross section of the part to be softened, is placed between the 15 electrode 1 and another electrode 3. The electrical connections are made to the electrodes 3 and 1, diagrammatically shown at 4 and 5. A high current is then passed through the electrodes and the resistor. 20 The density may be of any desired value, but I have found that the best results are obtained when using currents of densities varying between 500 and 5000 amperes per square inch. Substantially all the current 25 is concentrated inside the central part of the electrode 1 and this part will be quickly heated to a high temperature, while the remaining part of the electrode 1, will not be heated to such an extent, since the current 30 spreads over the entire section of it. The contact between the resistor and the electrode will have a comparatively high resistance and a great amount of heat will be developed there. The radiation of this heat 35 into the central core of the electrode end, together with that developed in the core by the current is concentrated therein, and will soon graphitize or soften this part while the remainder will not be graphitized. This 40 process results in a saving of electrical energy as only enough energy is required to graphitize the part within the dotted line 6.

In Fig. 3 I have shown how the outer shell of the electrode 1 may be softened at 45 one end. The electrode is circular and hence the resistor 7 is circular as is shown in Fig. 4. This resistor will have substantially the same cross sectional area as the part to be softened on the electrode 1. The current is 50 concentrated in the outer shell 8, and the heat developed in this part of the electrode, aided by the heat from the resistor contact, quickly converts it into graphite while the remainder is substantially unchanged.

55 In Fig. 5 I have shown an arrangement whereby a softened core may be made in one end of the electrode 1 at the same time that the softened shell is made in the other end of the electrode. This arrangement is 60 the combination of those shown in Figs. 1 and 3. Since the contact resistance causes a great amount of heat to be developed it is 65 advantageous to use a plurality of short resistors, and such have been shown in Fig. 5. I have found it advantageous to apply pres-

sure to the ends of the electrodes 3—3, and this is diagrammatically indicated by screws 9—9, the arrows P, P indicating the direction of pressure. However, my method is not limited to the use of pressure as it can 70 be carried out by merely placing the resistors in contact between an electrode to be treated and the terminal electrodes.

In Fig. 6 a plurality of electrodes are spaced apart and the spaces are bridged by 75 a plurality of resistors. The current then traverses the whole in series. This arrangement permits the use of a higher terminal voltage, which is an advantage. The series arrangement is the more efficient as the 80 losses in the external circuit are no greater than when only one electrode is treated.

In Fig. 7 is shown a box 15 made of some heat resisting material such as transite board. This box is first filled with crushed 85 charcoal or some other heat insulating material to the depth of several inches. The electrodes 1 are then placed on the charcoal and properly spaced. The ring sections 7 are then placed in alternate spaces. The 90 remaining spaces are partially filled with crushed charcoal and the sections 2 placed on top. The terminal electrodes 3, 3 are then forced against the carbon plates 16, to firmly clamp the arrangement together and 95 the box 15 is then entirely filled with crushed charcoal to retain the heat. The current is then turned on and in a short time the local parts will be softened as previously described.

In Figs. 10 and 11, I have shown modifications where the resistors are formed integral with the terminal electrodes. On the electrode 10 a tenon 12 is formed. The cross sectional form and area of the tenon 105 should be substantially the same as that of the core to be softened. The terminal electrode 11 has a shell 13 similar to the resistor 7 in Figs. 3 and 5. The cross sectional shape and area of this shell should correspond with that of the part to be softened.

In Fig. 8 the electrode 1 is shown after having been locally softened by my process and machined and screw threaded. The right hand end of this electrode is shown 115 in cross section to properly show the screw threaded socket.

In Fig. 9 the resistor 14 is shown rectangular in cross section. This form of resistor would be used to soften the outer shell 120 of a rectangular electrode. It will be understood that the shape of the resistor will depend upon that of the part to be softened.

In Fig. 12 the electrode 1 is first hollowed out as shown, before it is baked. Very little work is required to do this while the electrode is green. The terminal electrode 3 is placed in a vertical position, as shown, and the terminal electrode 3 is inserted, but not allowed to touch the electrode 1. 130

Granular conducting material 17, such as coke or graphite, is then packed loosely in the space around the electrode 1. In order to confine the current where it is needed the electrode 3 may rest on a block 18 of charcoal which is substantially a non-conductor of electricity. This block is placed in the cavity before the terminal electrode is placed therein.

10 In Fig. 13 the male and female ends of the electrodes 1 are cut as shown, while they are green and then they are softened by the electric treatment. The tenon may be softened by means of the resistor rings 15 while the socket may be softened by using the means shown in Fig. 12 previously described. A resistor block 19 resting against the non-conducting blocks 18 forms part of the electric circuit at the junction of the 20 two electrodes. Part of the current will also flow directly from one electrode through the granular material 17 to the other electrode. The entire current, however, must enter and leave the surface of 25 the sockets through the granular material and at these surfaces the contact resistance causes a great amount of heat to be generated, which together with the heat developed in the part 6 soon softens this part.

30 Instead of a charcoal block 17 being used, a carborundum block can be utilized providing the temperature is not carried too high.

In Fig. 14 special shaped resistors are 35 shown for softening the carbon on the male connection. The resistors may be made in two or more sectors if desired. The current enters the electrode ends at the outer surface, and hence the heat caused by the contact resistance is most desirably located. In Fig. 15 the resistor is shown in cross section, the section being taken on the line B-B of Fig. 14.

In Fig. 16 the resistor 21 is shown composed of only one part. The absence of the central dividing contact surface causes less heat to be developed, but this type of resistor might be more convenient to manipulate.

50 In Fig. 18 the resistor is shown as being composed of a plurality of concentric sleeves. The plurality of contacts will increase the heat.

In Fig. 19 the resistor is composed of a 55 plurality of rings 22 and a plurality of rings 23, the latter having a greater radial thickness. The electrodes 1 make a close fit through the rings 22 and abut against the rings 23.

60 In Fig. 20 a different arrangement is shown. The resistor 20 is shaped similarly to that in Fig. 12, but it is made larger. The central bore 23 makes a snug fit with the ends of the electrodes 1. The ends are 65 not in contact with each other, however,

They are pushed into the bore 23 only far enough to prevent granular material from filling the space between the ends. Granular material 17 is packed loosely in the space around the electrode ends as shown. The current is compelled to leave and enter through the outer surfaces of the electrode ends and the heat developed there is intense.

The arrangements shown in Figs. 10, 12, 14, 16, 18, 19 and 20 are intended to be used 70 to soften the parts on the male end of the electrodes. These arrangements, as are those shown in all the other figures, are intended to be coupled up appropriately in some box form as is shown in Fig. 6.

75 My process could be carried out with many different forms of apparatus, and since they form no part of the invention claimed in this application, the apparatus has been shown only in diagrammatic form. 80 In my application Serial No. 695,354 of May 6th, 1912, I have disclosed a special type of furnace that would be well suited to carry out this process.

85 It is not necessary to carry the temperature high enough to convert the local parts into graphite. I have found that carbon when heated up to temperatures varying between 1500 and 2200 degrees centigrade becomes soft and appears to be changed into 90 an allotropic form. I call this form super-baked carbon. This form, while not so soft as graphite, is a great deal softer than ordinary hard baked carbon and is readily machined. This process therefore can give 100 satisfactory results if the temperatures are carried no higher than the limits just specified.

95 Having described my invention what I claim is:

105 1. The method of softening a part of the end of an electrode which consists in placing a resistor having less cross section than the electrode end in engagement therewith, and passing an electrode current through 110 the resistor and the electrode.

2. The method of softening a part of the end of an electrode which consists in sending a current therethrough and causing substantially all of it to traverse said part of 115 the end.

3. The method of softening the outer part of the end of an electrode which consists in placing a shell resistor in contact with the end thereof, and passing an electric current through the shell and the electrode.

120 4. The method of softening the outer part of the end of an electrode which consists in sending a current therethrough and causing substantially all of it to flow through the said outer shell.

125 5. In apparatus for locally softening carbon articles, a carbon resistor having two central bores, one being of greater diameter than the other, whereby an internal shoul-

der is formed adapted to abut against the end of the article to be softened.

6. In apparatus for locally softening carbon articles, a resistor composed of a plurality of carbon sleeves, the inner sleeve being adapted to receive the ends of the articles to be softened.

In testimony whereof I have hereunto signed my name.

JOHN W. BROWN.

Corrections in Letters Patent No. 1,084,129.

It is hereby certified that in Letters Patent No. 1,084,129, granted January 13, 1914, upon the application of John W. Brown, of Lakewood, Ohio, for an improvement in "Methods of Softening the Ends of Electrodes and Other Carbon Articles," errors appear in the printed specification requiring correction as follows: Page 3, line 110, for the word "electrode" read *electric*; same page, line 126, for the word "shell" read *part*; and that the said Letters Patent should be read with these corrections therein that the same may conform to the record of the case in the Patent Office.

Signed and sealed this 3rd day of February, A. D., 1914.

[SEAL.]

J. T. NEWTON,

Acting Commissioner of Patents.
